UNITED STATES PATENT OFFICE.

THOMAS H. SELFERT, OF SPRINGTOWN, PENNSYLVANIA.

MOLD.

Application filed July 23, 1926. Serial No. 124,452.

This invention relates to a mold designed primarily for use in the construction of concrete burial vaults and sarcophagi, one of the objects of the invention being to provide a knock-down mold the parts of which can be assembled readily and wherein the concrete structure can be quickly and accurately formed and the mold subsequently removed therefrom without injury.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a side elevation of the mold set up in the formation of the body portion 25 of a vault.

Figure 2 is a top plan view thereof with the top plate removed.

Figure 3 is a perspective view of a portion of the pallet.

Figure 4 is a plan view of the inner form of the mold, one of the spreading wedges being removed.

Figure 5 is a detail view of one of the spreading wedges, a plate being removed 35 from one side thereof.

Figure 6 is a view partly in transverse section and partly in end elevation showing the mold with the concrete therein.

Figure 7 is a top plan view of the mold 40 used in the formation of the top of a vault.

Figure 8 is a bottom plan view of the pallet forming a part of said mold.

Figure 9 is a longitudinal section through the top forming mold, a portion thereof 45 being filled with concrete.

Figure 10 is a side elevation of the top forming mold.

Figure 11 is an end elevation of said mold.

Figure 12 is a transverse section through 50 the top plate of the top forming mold, the same being shown extended.

Figure 13 is a transverse section through

the top plate of the top mold showing the same collapsed.

Figure 14 is a sectional perspective view 55 of a portion of a bolt such as produced by a mold constituting the present invention.

Figure 15 is an elevation of a portion of a modified form of mold.

Referring to the figures by characters of 60 reference 1 designates a pallet in the form of an open frame the end portions of which are mounted on cross strips 2 suitably fastened to the pallet. Formed on the pallet or secured thereto is a rib 3 extending continuously along the sides and ends but spaced inwardly from the outer edges. Another rib 4 is extended continuously along the sides and ends of the pallet at the inner edges thereof. Secured to the bottom of the 65 pallet at the sides thereof are plates 5 the ends of which project outwardly from the sides and are formed with slots 6.

Side panels 7 are adapted to be supported in upstanding positions by the side portions 75 of the pallet 1, these panels being fitted against the outer sides of the rib 3. Each side panel 7 has tongues 8 extending downwardly therefrom and adapted to be inserted into the slots 6. Grooves 9 are provided in the inner spaces of the side panels where they will receive the ends of end panels 10 mounted on the end portions of the pallet 1 and bearing against the adjacent portions of the rib 3. Slots 11 are formed in 80 the side panels 7 and projecting through these slots are tongues 12 extending from the ends of the end panels 10. These tongues are provided with slots 13 for the reception of wedges 14. It will be apparent, therefore, that by inserting these wedges the side and end panels will be held together securely 85 and will be maintained at the proper angles to each other by the rib 3.

The inner form of the mold is made up of 90 angular corner panels 15 adapted to rest upon the pallet 1 and to bear inwardly against the rib 4. One portion of each corner panel forms part of one side of the form while another portion of each corner panel 100 forms a part of one end of the form. When the four corner panels are properly mounted they will be spaced apart at their ends as indicated, for example, at 16, the adjoining

ends of the panels being inclined so as to converge downwardly. A wedge 17 is adapted to be inserted between the downwardly converging ends of the corner members or panels, each wedge being secured between two face plates 18 which project beyond the edges of the wedge. The wedge is of substantially the same thickness as the panel so that it can be inserted downwardly 10 between the converging ends of the panel while at the same time the plates 18 will lap the outer and inner faces respectively of the panels. This has been clearly shown in Figures 2 and 4. Braces 19 can be secured 15 in the angles of the corner panels so as to prevent distortion of the form after it has been set up on the pallet.

The parts thus far described are assembled by erecting the panels 7 and 10 on the pallet 20 and securing them together by means of the wedges 14. The inner form is then erected on the pallet and the corner sections thereof are adjusted by means of the wedges 17 until the inner form is properly positioned relative to the outer form so that the space between the forms will be of uniform width. The concrete is then poured into this space and allowed to set. Before this is done, however, a cover plate 20 is positioned on the inner form so as to support that portion of the concrete which is deposited on the inner form. The rib 3 will produce a continuous rabbet in the edge portion of the molded article, it being understood that the body portion B of the vault is produced in this mold. The rabbet referred to has been indicated at R in Figure 14. After the body portion has thus been formed in an inverted position as shown in Figure 6, it can be turned over and will then be ready to receive its cover.

For the purpose of producing the top of the vault a mold such as shown particularly in Figures 7 to 13, is used. This mold includes a pallet in the form of an open frame 21 having cross strips 22 for supporting the same. Tongues 23 are extended laterally from the bottom of the pallet and have slots 24 therein. A rib 25 is formed on or secured to the pallet and extends continuously therearound, this rib being spaced inwardly from the edges of the pallet. Side panels 26 are adapted to be mounted on the side portions of the pallet and have tongues 27 secured thereto and extending downwardly therefrom for insertion into the slots 24 in tongues 23. Each of these side panels 26 has grooves 28 in its inner side for the reception of the ends of the end panels 29 and tongues 30 are extended from the ends of the end panels through slots 31 in the side panels 26, these tongues being adapted to receive wedges 32 whereby the panels 26 and 29 are held together securely.

The top plate of this mold is formed of

opposed frames 33 each of which is provided with an arcuate top 34, the tops of the two frames being hingedly connected as at 35. The meeting portions of the frames are beveled as shown at 36 so that it is thus possible for the frames to partly collapse as shown in Figure 13. Any suitable means such as hook 37 and a lug 38 are provided for holding the frame extended as shown in Figure 12. When the structure is thus extended it is adapted to rest upon the pallet 21 against the inner surfaces of the rib 25 as shown particularly in Figure 9. With the parts thus located the concrete of which the top of the vault is to be formed is poured into the mold and over the top thereof as shown at C in Figure 9. By providing the rib 25 located as shown the molded cover C will be formed with a continuous rib C' (see Figure 14) which is adapted to rest in the rabbet R of the body portion of the vault.

After the cover has been molded and properly set, the same is inserted and thereafter the mold can be readily disengaged therefrom. The pallet can be easily lifted from engagement with the tongues 23 after which the side panels can be readily disengaged from the end panels. By then collapsing the hingedly connected frames 33, as shown in Figure 13, they can be disengaged from and removed from the molded cover.

In some forms of molds it is desirable to provide the pallets with bracing means to prevent sagging. One such arrangement has been illustrated in Figure 15 wherein the pallet 39 has been shown provided with a strut 40 extending longitudinally thereunder and anchored at its ends to the pallet as shown at 41.

Obviously instead of forming this mold of wood, as shown, it can also be made of metal, such construction requiring but slight modifications in the arrangement and construction of the parts.

What is claimed is:

1. In a mold the combination with a pallet and a collapsible outer form removably mounted thereon, of an inner form including a plurality of angular corner panels, one of said panels being provided for each corner of the inner form, the said panels being spaced apart at the centers of the sides and ends of the form, wedges insertible downwardly between the panels within the respective spaces between the ends thereof, said wedges being independently adjustable, and means carried by each wedge and cooperating with the engaged panels for holding the wedge against lateral displacement relative to the engaged panels.

2. In a mold the combination with a pallet and a collapsible outer form mounted thereon, of an inner form consisting of

angular corner members, said members being spaced apart at their ends and having said spaced ends converging downwardly, wedges insertible downwardly between the converging ends of the corner members, thereby to adjust the inner form to different lengths and widths, said wedges being separately movable, and face plates upon opposite faces

of each wedge for lapping the ends of the engaged corner members, thereby to hold 10 the wedge against lateral displacement relative to said members.

In testimony that I claim the foregoing as my own, I have hereto affixed my signature.

THOMAS H. SEIFERT.
